Application filed May 20, 1899. Serial No. 717,646. Term of patent 3½ years.

To all whom it may concern:

Be it known that we, FRANCIS E. WILKINSON and CALVIN D. KINGSTON, citizens of the United States, residing at Buffalo, in the county of Erie and State of New York, have invented and produced a new and original Design in Badges or Like Articles, of which the following is a specification, reference being had to the accompanying drawing, forming a part thereof, in which is illustrated a plan view of our new design.

As shown in the drawing, the leading feature of the design consists of a circular plate 1, upon which is illustrated a picture of a buffalo 2, having a series of brownies or mani-

kins 3 on its back. Upper and lower panels 4 and 5 are arranged, respectively, above and below the buffalo and afford space for suitable words or legends.

Having described our invention, what we claim as new, and desire to secure by Letters Patent, is—
